DISAPPEARING STAIRWAY

Willard D. Eakin, Akron, Ohio

Application September 14, 1943, Serial No. 502,292

6 Claims. (CL 228-50)

This invention relates to disappearing stairways.

Its chief objects are:

To provide simplicity, economy and durability;

To provide a stairway and associated mechanism adapted to be stored wholly within the space between two ceiling joists, so that when the parts are in stored position the floor of the upper room can be continuous and unobstructed;

To provide a stair of this type which will not be excessively steep when in use position;

To provide an improved combination of a stair and trap-door and mechanism so connecting them that actuation of one will automatically actuate the other so that they can be moved to and from use position from either the upper floor or the lower floor;

To provide a trap-door and stair so counter-balancing each other that they can be moved to and from use position with little effort, and to provide an "over-center" effect so that the assembly will be firmly held in use position by gravity and will be firmly held in stored position by gravity;

To avoid the use of cable-and-pulley devices and of springs for counteracting the weight of the stair, and thus to eliminate their disadvantages of wear, breakage and danger;

To provide numerous and widely spaced points of support for the stair when in use and when being moved to and from stored position;

To provide automatically presented and automatically stored hand rails;

To provide other advantages which are inherent in the structure herein described.

Of the accompanying drawings:

Fig. 1 is a vertical middle section of a stair and associated structure embodying my invention in its preferred form.

Fig. 2 is a section, on a larger scale, on the indirect line 2-2 of Fig. 1.

Fig. 3 is a section on line 3-3 of Fig. 1.

Fig. 4 is a section on line 4-4 of Fig. 1.

Referring to the drawings, the mechanism is shown installed in a room of which the studding is shown at 10, 10; the plates at 11, 11, one of the joists at 12, boards of the upper floor at 13, 13, and the floor of the lower room at 14.

The stair, 15, is provided on each side of its upper end with an outwardly projecting axle-and-roller assembly 16, the rollers being of grooved or waisted form and adapted to run horizontally in respective track-ways, such as the one shown at 17, secured to the respective joists at the two sides of the stair.

The track-ways 17 are the same in cross-sectional form as track-ways, such as that shown at 18, which are secured by screws 19, 19 (Fig. 3) to the outer faces of the side members of the stair, and the rollers 16 are of the same construction as the rollers that are adapted to run in the track-ways 18, one of which rollers is shown at 20 (see Fig. 3).

Secured to each of the joists, 12, by screws 21, 21, is a face plate 22 formed with two holes in which respectively are riveted a large, shouldered axle-stud 23 and a smaller, shouldered axle-stud 24, projecting toward the middle of the stair well.

Each of the studs 24 is connected with a stud 25 projecting from the adjacent side of the stair by a thin, flat link member 26, which is adapted to act as one arm of a toggle, of which the other arm is the upper portion of the stair, for shifting the upper end of the stair to the right, along the guide-ways 17, when the stair is swung upward about the moving axis 16. Thus the upper end of the stair moves to the position *a* as its lower end moves to the position *b*.

This shifting-axis feature permits the use of a stair almost as long as the ceiling joists, so that it is not excessively steep when in use, and at the same time provides upper and lower landings of adequate size.

An opening 27 in the floor of the upper room is adapted to be closed by a trap-door 28 which is hinged at 29. The trap-door preferably but not necessarily consists of flooring boards 13^a, 13^a, held together preferably by a sheet-metal plate 30 secured to their under faces by screws such as the screw 31 (Fig. 4) along the side margins of the metal plate, near the ends of the boards 13^a, so that the metal plate serves as a bridge member to give the door great strength for supporting weight whether or not the plate 30 itself directly engages the joists. Permissibly it can come to rest upon the upper edges of the axle-stud plates 22 (compare Figs. 4 and 2).

Secured to the lower face of the plate 30 are a pair of guide-ways of which one is shown at 32 for guiding respective rollers such as the roller 33, which can be of the same size and construction as the two other pairs of rollers 16 and 20. For economy each of the six rollers can be formed of three sheet-metal discs spot-welded together.

For providing such mechanical connection between the stair 15 and the trap-door 28 that they will counter-balance each other, with the "over-center" effect above referred to in the statement of objects, the rollers 33 are mounted respectively upon the upper ends, and the rollers 20 are

mounted respectively upon the lower ends, of a pair of actuating levers of which one is shown at 34, said levers being fulcrumed respectively upon the axle-studs 23.

When the trap-door 28 and its metal reinforcing plate 30 are of sufficient size and weight they can alone serve as a sufficient counter-weight for the stair, but if the proportions and weights of parts are not such as to provide adequate counter-weight without more a special counter-weight 35, adapted to be received between steps of the stair, can be secured to the under face of the door.

The structure thus far described provides a simple, dependable, safe and durable mechanism 15 for installations where hand-rails paralleling the stair are not required, the nearly vertical actuating levers 34 and the angularly disposed links 26 serving well as hand-holds.

Such construction is well adapted, however, for combination with a pair of hand-rails, such as the one shown at 36, hinged respectively upon the axle-studs 24 and at a lower position connected with the stair by parallel-motion links such as the link 37 having the same effective length, between pivots, as the toggle-links 26.

Bracket-like clips such as those shown at 38 and 39 can be mounted on the link 37 and hand-rail 36 respectively and adapted to receive the actuating lever 34 as the stair comes to use position, for giving the hand-rail additional points of support against lateral displacement.

The mechanism can be operated either from the upper floor, by manual engagement of the trap-door, which preferably is provided with an in-set handle ring 40, or from the lower floor, by manual engagement of a pull cord 41a attached to the stair. Only a small force is required for moving the assembly from the dotted-line stored position to the full-line use position, or back to the stored position. The stored position of the actuating lever 34 is shown at c and that of the hand-rail 36 at d.

A panel 41 of ceiling material or of ply-wood can be secured to the under side of the stair, so that when the stair is in stored position the opening in the ceiling will be closed by it. It also serves the purpose of "risers," which is of some importance in view of the fact that some persons dislike to use stairs that they can see through.

Preferably a bar 42 of triangular cross-section is secured to the lower end of the stair and, like the panel, projects to the middle plane of the joist at each side, to serve as a large-area foot for the stair and as a stop for the stair in its stored position, the projecting end portions of the foot abutting the under edge faces of the joists.

It is clear from an inspection of Figs. 2, 3 and 4 that only a very narrow space is required for the mechanism at each side of the stair, especially when the strip members are of sheet metal, and that they can be of such thickness as to be made of wood without very much increase of the width of those spaces.

The parts are firmly held in use position by gravity because when they are in that position the weight of the door assembly is sustained largely by its hinges 28, with only a small torque force sustained by the actuating levers 34, and also because the weight of the stair has a substantial mechanical advantage by reason of the angular relation of the guide rails 18 and the levers 34.

The parts are strongly held in stored position

by gravity because when they are in that position the actuating bars 34 sustain a greater part of the weight of the door assembly, with only about half of the weight of the stair sustained by the bars at their other ends, and with no mechanical advantage for either other than the difference in the lengths of the lever arms, which is not a dominating factor.

This "over-center" effect can be had throughout a wide range of relative dimensions and relative weights of parts, without changing the leverage position or size of the counterweight. Correspondingly, the assembly does not involve any difficult balancing problem.

A longer range of movement of the upper end of the stair can be provided by using a shorter stair or increasing the length of the toggle arms, or by doing both. The structure is such that the device can be operated from either the upper floor or the lower floor even when the parts are so proportioned that the angle between the links 26 and the upper end portion of the stair is substantially less than a right-angle.

Various modifications are possible without sacrifice of all of the advantages set forth in the above statement of objects and without departure from the scope of the appended claims.

I claim:

1. The combination of a stair having moving-pivot mounting means at its upper end, a link having a fixed axis at one end and pivoted to the stair at its other end, a hand rail pivoted on the said fixed axis, and a second link connecting the hand-rail with the stair, the hand-rail, the two links and the stair constituting a parallel-motion.

2. A stairway assembly comprising a pair of horizontally disposed, spaced-apart, side members, a floor supported by said members and having a stair-opening between them, runway means disposed at least approximately lengthwise of, and on the inner face of, said members, a stair-runner means on the upper end portion of the stair for coaction with said runway means, and a link having one of its axes fixed with relation to one of said side members and its other axis fixed with relation to the stair.

3. A stairway assembly comprising a floor structure having a stair-opening therein, at least approximately horizontal runway means mounted

in fixed relation to and below the upper face of said floor structure, a full-length, rigid stair-runner means on the upper end portion of the stair for coaction with said runway means, the runway means and the runner means constituting a moving-pivot connection about which the stair can be swung upward to stored position and downward to use position, and means for stopping the stair in use position, the dimensions and positions of the recited elements being such that when in use position and also when in stored position the stair is wholly below the upper face of said floor structure and wholly within its horizontal limits and, when in stored position, is wholly disposed in an at least approximately horizontal position,

65 the assembly including a hand-rail and means so connecting it to the floor structure and to the stair as to cause it to lie close to and at least approximately parallel to the stair when the latter is in stored position and to be brought to use position by swinging of the stair to use position.

4. A stairway assembly comprising a floor structure having a stair-opening therein, at least approximately horizontal runway means mounted in fixed relation to and below the upper face of said floor structure, a full-length, rigid stair,

runner means on the upper end portion of the stair for coaction with said runway means, the runway means and the runner means constituting a moving-pivot connection about which the stair can be swung upward to stored position and downward to use position, and means for stopping the stair in use position, the dimensions and positions of the recited elements being such that when in use position and also when in stored position the stair is wholly below the upper face of said floor structure and wholly within its horizontal limits and, when in stored position, is wholly disposed in an at least approximately horizontal position, the combination including a trap-door hinged to the floor structure for closing the stair opening, runway means on the trap-door, runway means on the stair, a lever fulcrumed on an axis fixed with relation to the floor structure, and runner means on respective arms of the lever for coacting with the last mentioned two runway means respectively.

5. A stairway assembly comprising a floor structure having a stair-opening therein, at least approximately horizontal runway means mounted in fixed relation to and below the upper face of said floor structure, a full-length rigid stair, runner means on the upper end portion of the

stair for coaction with said runway means, the runway means and the runner means constituting a moving-pivot connection about which the stair can be swung upward to stored position and downward to use position, and means for stopping the stair in use position, the dimensions and positions of the recited elements being such that when in use position and also when in stored position the stair is wholly below the upper face of said floor structure and wholly within its horizontal limits and, when in stored position, is wholly disposed in an at least approximately horizontal position, the combination including a trap-door hinged to the floor structure for closing the stair opening, and means so connecting the stair and the trap-door that movement of one of them toward vertical position and toward horizontal position effects corresponding movement of the other.

6. A ladder assembly comprising a supporting structure having at least approximately horizontal runway means thereon, a ladder having at one end runner means hingedly associated with said runway means, and a link having one of its axes fixed with relation to said supporting structure and its other axis fixed with relation to the ladder.
